UNITED STATES PATENT OFFICE

RALPH C. ROE, OF ENGLEWOOD, NEW JERSEY

PULVERIZED FUEL BURNER

Application filed January 9, 1928. Serial No. 245,425.

This invention relates to fuel burners, and more particularly to pulverized fuel burners, and comprises all improvements over the prior art which are disclosed in this application.

One object is to provide a quicker and more complete combustion of the fuel by securing more rapid, thorough and intimate mixture of the combustible and the air for combustion. One advantageous way of accomplishing this is to project a stream of fuel and air mixture, and project against said stream, secondary air in the form of a number of separate streams, each stream of secondary air being alternately increased and decreased in volume, but preferably not all the streams acting in unison. The secondary air streams are preferably controlled in groups in such manner as to strike the stream of fuel and air mixture from alternate directions and with variable volume so as to induce rapid, thorough and intimate mixture of fuel and air.

The above and other objects which will hereinafter appear, are attained by the new and useful improvements disclosed in this application. To enable others skilled in the art to fully understand the essential characteristics of the improvements, drawings illustrating one mode of carrying out the invention have been annexed as part of this disclosure.

Fig. 1 is a view looking from the furnace toward the face of the burner.

Fig. 2 is a sectional view on the plane indicated by line 2—2 of Figs. 1 and 5.

Fig. 3 is a fragmental sectional view on the plane indicated by line 3—3 of Fig. 4.

Fig. 4 is a sectional view on the plane indicated by line 4—4 of Fig. 1.

Fig. 5 is a sectional view on the plane indicated by line 5—5 of Fig. 2.

Fig. 6 is a perspective view of an intermediate fragment of one of the rotary valves.

One form of apparatus for carrying out the invention comprises a burner 1 having water-cooling tubes 6 which are part of the water-cooled wall surface of the boiler. Tube-face blocks 7, which may or may not be refractory faced, are preferably in intimate contact with tubes 6. The passage 8 for carrying the mixture of fuel and primary air

is central of the burner and tapers toward one end. Passages 9 for the secondary air, are arranged on each side of, and taper in the opposite direction to, passage 8, thus providing a very compact construction. 55 Shaft 10 may be driven from any suitable power source and also carries a gear 11 from which a chain 14, preferably a silent chain, drives gears 12 secured on reduced shaft extensions of valve cylinders 13. 60

Passage 8 has a long, narrow side slot merging with opening 15 which opens out through the bottom of recess 4. Each passage 9 has a long side-opening which connects with a cylindrical shaped opening occupied by a 65 valve cylinder 13. Each valve cylinder 13 has a series of alternate openings 2 parallel to each other, and another series of alternate openings 3 which are parallel to each other but transverse to openings 2. In the apparatus illustrated, openings 2 are at right angles to openings 3.

Along each side of opening 15 is a series of secondary air openings 16 to 37. When the corresponding valve 13 is turned to one position, its openings 2 provide communication between one passage 9 and alternate secondary air openings 18, 22, 26, 30, 34; and when turned at right angles, openings 3 provide communication between the same passage 9 75 and alternate secondary air openings 16, 20, 24, 28, 32, 36, communication between passage 9, and openings 18, 22, 26, 30, 34 being shut off. Similarly, the other valve 13 controls the odd numbered secondary air openings 17 80 to 37 on the other side of opening 15.

The valve or control cylinders 13 are so timed by means of their gear relations that openings 17, 21, 25, 29, 33, 37 on one side, and alternate openings 18, 22, 26, 30, 34 on the 85 other side, are controlled in unison, while openings 19, 23, 27, 31, 35 are controlled out of unison with the openings 17, 18, 21, 22, 25, 26, 29, 30, 33, 34, 37, but in unison with the alternate openings 16, 20, 24, 28, 32, 36 on the 90 other side.

Operation.

In operation, the fuel and primary air mixture enters passage 8 and passes laterally out 100

through the long narrow opening 15 as an evenly distributed wide thin stream. Suitable power being applied to shaft 10 at a suitable rotative or reciprocating speed by means of chain 14 and gears 11, 12, the openings 16 to 37 are controlled as previously explained, so that the secondary air which enters passages 9 leaves openings 16 to 37 in volume and at times to be now explained more fully. Since as previously explained, openings 17, 21, 25, 29, 33, 37 on one side act in unison with alternate openings 18, 22, 26, 30, 34 on the other side, when the valves 13 start to permit passage of secondary air out of these openings, this secondary air emerges as a number of separate streams from the walls of recess 4 and strikes against opposite alternate places of the fuel and primary air mixture stream which emerges straight out from the bottom of recess 4. As the valves 13 continue their movement, the volume of this secondary air increases to a maximum, then decreases to a minimum, then again increases to a maximum, and so on. While this is going on, the other openings 19, 23, 27, 31, 35 and alternate opposite openings 16, 20, 24, 28, 32, 36, are acting similarly but in exactly opposite phase. That is, when the first described openings 17, 21, 25, 29, 33, 37, 18, 22, 26, 30, 34, are at a maximum, openings 19, 23, 27, 31, 35, 16, 20, 24, 28, 32, 36, are at a minimum, and conversely. This cycle is repeated indefinitely.

In consequence of this action, the secondary air in the form of separate relatively thin streams, strikes the stream of fuel and primary air mixture from opposite, alternate, shiftable directions, in variable volume, producing a high state of agitation and extremely quick and thorough mixture of the fuel and air for combustion.

The number and size of the secondary air openings may be varied to provide any desired lesser or greater number, as also may the rapidity of the changes of direction and volume of secondary air, thus allowing change of type of agitation in any degree desired. The alternate groups of openings in valves 13 may be at other angles than right angles, and the mechanism may be so constructed that the secondary air streams will alternate without any appreciable time when both sets of secondary air streams will be functioning at once.

The invention may be embodied in other specific forms without departing from the spirit or essential characteristics of the invention, and the present embodiment is therefore to be considered in all respects as illustrative and not restrictive, the scope of the invention being indicated by the appended claims rather than by the foregoing description, and all changes which come within the meaning and range of equivalency of the

claims are therefore intended to be embraced therein.

I claim:

1. A fuel burner comprising, fuel and primary air mixture outlet means designed to project a stream of fuel and primary air mixture continuously, secondary air outlet means closely adjacent said first mentioned means and designed to project secondary air against the stream of fuel and primary air mixture, and power drivable control mechanism designed to alternately increase and decrease the volume of air from different parts of said secondary air outlet means.

2. The fuel burner of claim 1 in which the secondary air outlet means comprises a plurality of openings.

3. The fuel burner of claim 1 in which the secondary air outlet means comprises openings arranged in a plurality of groups, the openings of any one group being controlled in unison.

4. A fuel burner comprising, long fuel and primary air mixture outlet means, a line of secondary air outlet openings along each side of the fuel and primary air mixture outlet means, and power drivable control mechanism to alternately increase and decrease the volume of air from each opening.

5. The fuel burner of claim 4 in which the power drivable control mechanism is designed to alternately increase and decrease the volume of air from certain openings on one side while alternately decreasing and increasing the volume of air from corresponding openings on the other side, and conversely.

6. A fuel burner comprising, long fuel and primary air mixture outlet means, long secondary air outlet means closely adjacent and along the fuel and primary air mixture outlet means, and a power drivable rotary valve for the secondary air outlet means substantially coextensive with the secondary air outlet means.

7. A fuel burner comprising, long fuel and primary air mixture outlet means, two long secondary air outlet means, one closely adjacent and along each side of the fuel and primary air mixture outlet means, and a separate power drivable rotary valve for each secondary air outlet means.

8. The method of mixing a fuel and primary air mixture with secondary air which comprises, projecting a stream of fuel and primary air mixture continuously, and projecting secondary air against the stream of fuel and primary air mixture adjacent where the mixture is projected with different parts of said secondary air alternately increasing and decreasing in volume.

9. The method of claim 8 which comprises projecting secondary air as a plurality of streams.

10. The method of claim 8 which comprises projecting secondary air as a plurality of

streams, certain of said streams being controlled in unison.

11. The method of claim 8 which comprises projecting secondary air as a plurality of groups of streams, the streams of any one group being controlled in unison, and one group being controlled out of unison with another group.

12. The method of claim 8 which comprises projecting secondary air as streams along each side of the fuel and primary air mixture, certain streams on one side being controlled out of unison with corresponding streams on the other side.

13. The method of claim 8 which comprises projecting secondary air as groups of streams along each side of the fuel and primary air mixture stream, the streams of any one group being controlled in unison, and one group of streams being controlled out of unison with another group on the same side and also out of unison with its corresponding group on the other side.

14. The method of claim 8 which comprises projecting the fuel and primary air mixture as a thin wide stream.

15. The method of claim 8 which comprises projecting fuel and primary air mixture as a thin wide stream, and projecting secondary air as a plurality of streams the width of each of which is relatively great as compared with its thickness.

16. A fuel burner comprising, two side by side secondary air passage members tapering in the same direction and providing a limited space between and oppositely tapered to themselves, and a fuel and primary air mixture passage member occupying said tapered space and being tapered in the same direction as the tapered space.

17. A fuel burner having a burner face, long fuel and primary air mixture outlet means in said face, long secondary air outlet means in said face adjacent said mixture outlet means, power-drivable, long rotary valve mechanism in the burner to alternately increase and decrease the volume of air from different parts of said secondary air outlet means and extending in the same general direction as said face, and fluid-coolable means in the burner and extending in the same general direction as the rotary valve mechanism to prevent an undue rise of temperature of said valve mechanism.

55 In testimony whereof I hereunto affix my signature.

RALPH C. ROE.
